UNITED STATES PATENT OFFICE.

GLENN H. DRABENSTOTT, OF WOOSTER, OHIO.

REFILLABLE ELECTRIC FUSE.

Application filed December 13, 1920. Serial No. 430,582.

To all whom it may concern:

Be it known that I, GLENN H. DRABENSTOTT, a citizen of the United States, residing at Wooster, in the county of Wayne and 5 State of Ohio, have invented a new and useful Refillable Electric Fuse, of which the following is a specification.

My invention relates to improvements in electric fuses, and particularly to such as 10 are refillable, and its principal objects are, first, to provide a fuse of such character as to be fillable without the use of tools; and, secondly, to provide a re-fillable fuse constructed of one piece, the parts of which 15 need not be separated in order to refill the same by inserting a new fuse link therein, in lieu of one that has been burnt out; and, lastly, to provide a re-fillable electric fuse of such construction as to be handier and 20 less expensive, and more perfect than fuses of like character heretofore made.

My invention consists primarily in the construction of a re-fillable fuse in such manner that its parts may be assembled 25 readily, and, when so assembled, need not be taken apart in order to change the fuse link therein, but may remain as a single piece, adapted to be opened and shut by the rotary action of an enveloping sheath, having 30 a slot therein, adapted to register with a corresponding slot in the body of the fuse, when said sheath is rotated a predetermined distance; and, secondly, of improved means 35 for inserting and connecting the fuse link within the body of the fuse, and for exchanging an injured or burnt out fuse link without the use of tools.

My invention is illustrated by the accompanying drawing, in which similar letters 40 and figures of reference indicate like parts.

Referring thereto, Fig. 1 is a perspective view of a re-fillable electric fuse embodying my invention, one end thereof being removed for better illustration of the parts— 45 the two ends thereof being in all respects alike. Fig. 2 is a vertical longitudinal cross section of Fig. 1 on the dotted line 2—2 thereof, showing the relation of the several parts to each other. Fig. 3 is a side view of 50 a fuse link, such as I employ, for insertion within the body of the fuse; and Fig. 4 is a detail view of the block and end piece for insertion at each end thereof.

In the drawing, A is the outer sheath and 55 B the fuse body, the former having a longitudinal slot opening G from end to end

thereof, and the latter, a like slot opening H, said slot openings being adapted to register longitudinally with each other by the rotation of the sheath A upon the body B. D 60 is a block or end piece which is adapted to be inserted, one at each end of the body B, and may be secured therein by means of a set-screw j, or equivalent means. Its inner end is bifurcated, the parts e and f being 65 partly separated by a cavity b therein, as shown in Fig. 4.

An end-cap E covers each end of the fuse, being preferably secured thereto by means of the threaded thumbscrew bolt I, as best 70 shown in Fig. 2. Said bolts extend vertically through the end caps E and the body B adjacent thereto, and are threaded into the adjacent part e of the block D, and terminate with a swivel cap or disk i located 75 intermediate the parts e and f of the block. L L are flat members solidly connected to the blocks D D, respectively, such as are commonly used in fuses, and no claim specifically is made thereto. The fuse link F, 80 having thin flat ends g g, is also old, except in the manner of connecting it with the blocks at each end of the body of the fuse. It is readily inserted endwise and flatwise between the swivel disks i i and the abutments f f, respectively, by simply rotating the outer sheath A around the body B until the slot openings G H, respectively, are opposite each other, the ends of the fuse link dropping by gravity into the cavity b (Fig. 90 4), when it may be clamped therein by the thumbscrews I I, respectively, and then enclosed completely within the fuse by rotating said sheath to normal position, shown in Fig. 1. Said sheath is preferably held 95 removably in normal closed position by means of a resilient member located in the exterior portion of the body B, its central part being raised and adapted to removably enter within the hollow of a raised portion d in a corresponding part of the sheath, best shown in Fig. 2.

Heretofore, fuse links of similar form have been inserted within the body by removing an outer covering of said body, and 105 clamping the ends thereof upon the inner end of the extended flat member L, and securing the said parts together by means of screws or the like, access to which has been given by the removal of the outer covering 110 of the body, and such I do not broadly claim. My improvement lies in the construction and

organization of the related parts in such manner that the outer covering need not be removed, and in means for the removal or attachment of the fuse link, whereby screw drivers and other tools may be dispensed with in the operation, and the ends of the fuse link better secured by the means aforesaid, which afford larger surface bearings, and better opportunity for functioning the fuse.

Having thus fully described my invention, what I claim as new and desire to secure by Letters Patent is—

1. In a device of the character described, 15 the combination with a cylindrical body, having a longitudinal slot opening therein, of a cylindrical sheath enveloping said body, said sheaths having a longitudinal slot opening therein adapted to register with 20 said body slot by rotation over said body; bifurcated blocks in the ends of said body, respectively, and means, including screws passed from without said sheath through one of the abutments of said blocks, respectively, for fastening the parts together, and 25 a fuse link inserted edgewise into notches in said blocks, respectively, substantially as set forth.

2. In a re-fillable fuse, the combination

with a cylindrical body having a longitudinal slot opening therein, of a cylindrical sheath enveloping said body, and having a longitudinal slot opening therein adapted to register with said body slot by rotation thereover, means for removably securing 35 said cylindrical bodies in closed position when rotated, bifurcated head-blocks in the ends of said body, respectively, caps mounted over the ends of said bodies, respectively; an electric fuse link fitted to drop by gravity through said slots, its ends resting in cavities of said head-blocks, when said cylindrical body slots are in juxtaposition; and means, including manually operable screws passed through said end caps, body ends, 45 and adjacent abutments of said head-blocks, respectively, for connecting the ends of said fuse link, respectively, thereto and to said flat extensions from said blocks, respectively, substantially as set forth, and for 50 the purpose specified.

In witness whereof, I hereunto set my hand this 9th day of October A. D. 1920.

GLENN H. DRABENSTOTT.

In presence of two witnesses:

HIRAM B. SWARTZ,
CHARLES C. JONES.
